Patented Mar. 11, 1919.

UNITED STATES PATENT OFFICE.

FREDERICK WILLIAM RASMUSSEN, OF MANGARAMA, NEW ZEALAND.

MACHINE FOR USE IN MAKING WIRE STAPLES.

1,296,696.

Specification of Letters Patent. Patented Mar. 11, 1919.

Application filed August 14, 1918. Serial No. 249,843.

To all whom it may concern:

Be it known that I, FREDERICK WILLIAM RASMUSSEN, subject of the King of Great Britain, residing at Mangarama, in the Dominion of New Zealand, laborer, have invented a new and useful Improved Machine for Use in Making Wire Staples; and I do hereby declare the following to be a full, clear, and exact description of the same.

10 This invention has been devised in order to provide an improved construction of machine for use in making the ordinary type of U shaped wire staples used particularly in wire fencing and also for other purposes, 15 the machine being adapted especially for use by farmers and others in the making of the staples from lengths of wire and allowing of any odd lengths of wire being used up for that purpose.

20 The machine in its operation is designed by the one action of a lever handle, to sever a sufficient length of wire to form a staple from the main length by a cut forming the point of the staple leg, and then to double 25 up such severed length into the required U form and discharge it from the machine.

The machine devised for this purpose is illustrated in the accompanying drawings to which reference will be made in fully describing its construction and operation. In 30 such drawings:

Figure 1 is a side elevation.

Fig. 2 a front end elevation, and

Fig. 3 a plan (partly in section) of the 35 complete machine.

Fig. 4 is a sectional plan of a portion of the machine the section being taken on the line 4—4 of Fig. 1.

Fig. 5 is a sectional elevation of the upper 40 portion of the machine, taken on the line 5—5 of Fig. 3.

Fig. 6 is an inside elevation of the lever handle and its cutters.

Fig. 7 is a detail view of a length gage 45 used with the machine.

The machine is formed by a base block having a table portion A with a flat face that preferably slopes downward to one end, as shown in the drawings, and an upwardly 50 extending flange portion B on one side and the inner face of which is made to assume a vertical face to the surface of the table. This flange portion is also formed with a rearward extension B', projecting beyond the 55 upper end of the table A. Let into the surface of the face of the portion B—B' is the

steel plate C which is suitably tempered. This plate extends across the level of the table A and also covers the inside face of the extension B' the upper edge of the part 60 covering the extension forming a knife edge C' on its front corner. The plate C near its forward end is pierced with the aperture D that extends through it at an acute horizontal angle and at a height immediately above the 65 level of the table A and also in a line with the line of the table's surface. The flange B at the back of the plate C is formed with the opening D' extending from behind the aperture D upward and rearward to the 70 back end of the flange as shown particularly in Fig. 4. A wire E may thus have its end passed in through this opening D' and through the aperture D so that the end will project out at an angle across the table A 75 as also shown in Fig. 4 and in dotted lines in Fig. 5.

A disk plate F is provided and mounted on an axial pin G against the inside face of the flange B and plate C. This disk plate 80 is provided with the lever handle extension F' so that it may be turned and its inside face makes close contact with the surface of the plate C. The edge of the disk is formed with an opening F² and along the 85 upper edge of such opening is fixed a knife blade H the cutting edge of which is arranged approximately radially to the pin G so that when the disk plate is turned, the 90 blade will pass across the end of the aperture D. Consequently when a wire has been caused to project through such aperture, the projecting end may be severed by turning the disk so that the blade H engages and cuts through the wire, and by reason of the 95 said wire projecting at an acute angle from the face of the plate C, the wire will be cut in a corresponding angle so as to make points upon the ends of the severed and main portions. Thus the wire lengths severed by the machine will be pointed at both ends. The cut away portion F² in the disk's edge allows for the wire being projected through the aperture D in the required manner. The handle lever F' on its back edge 100 and at a suitable distance from the pin G is provided with the knife blade J that, when the handle is turned right back, passes across the surface of the knife edge C' so as to make therewith a shear by means of which 105 wire laid across the extension B' may be cut. This will allow for wire being freed 110

from any knotted or kinked portions that would serve to prevent it passing through the aperture D.

The table A is formed near its lower, or front end, with a slot opening K extending through it and this opening is preferably made in a removable plate K' that slides transversely into a groove formed in the table surface and having undercut edges to hold the plate from lifting. This permits of different plates having slots K arranged at different distances from the position of the aperture D, being used as required in the making of staples of different lengths in the manner hereinafter described. The width of the slot is made to correspond with the spread of the legs of the staple to be formed.

Pivottally attached to the disk handle F' is a forked claw M that is curved lengthwise and passes into the slot K so that as the handle is turned down to sever a length of wire, the claw will slide down through the slot. The fork is so disposed that the two members N—N' of the forked end will pass on the opposite sides of the wire lying across the slot K so that as the downward movement continues the top of such fork will engage the wire, double it up and carry it down through the slot. Sufficient clearance is left between the faces of the claw and the sides of the slot to allow for the wire ends passing down, but to insure of the bending resulting in the staple lengths being parallel to one another, guiding notches k (Figs. 4 and 5) are formed opposite one another in the sides of the slot K and the grooves m (Fig. 2) are formed in the sides of the claw extending up from the top of its fork. The wire ends therefore double up into these grooves. The fork of the claw is made of such a length, and the point of the claw's attachment to the handle lever F' is so adjusted, that in the operation of the machine, the forks will pass down over the projecting wire and lying across the slot K before it is cut and immediately it is cut the top of the fork will engage the severed length and double it up and force it down and drop the staple thus formed beneath the table.

To provide for staples of different lengths being formed, provision is made whereby the length of wire projected through the aperture D may be gaged to form a staple of specific length. Such provision consists in forming the extension B' with gage markings O at different points in its length so that when the wire end has been inserted through the opening D' and it is caused to engage with a solid portion of the disk, the operator may grasp the wire opposite the required gage marking and then (after the disk has been turned to allow the wire end to be projected through the aperture D) may feed such wire in until his fingers en-

gage the back end of the opening D'. The movement of the handle lever is then continued to cut the wire and to bend it in the manner described.

In order that the severed wire length may be positioned with its middle above the middle line of the slot and thus to insure of both legs of the staple being the same in length, a special gage plate P shown in side elevation in Fig. 7 is attached to the table A in the position shown in Figs. 1 and 2. This provides a stop P' extending across the table A below the slot K with which the end of the wire, as it is severed, engages and which stop is so positioned in relation to the slot 80, as to cause the middle of the wire to lie across such slot. This gage plate is adjustable in its position, being secured to the side edge of the table A by means of the set screw p passing through the slot p' formed longitudinally in the plate. This adjustability of the gage plate together with the adjustability of the slot K in relation to the aperture D already referred to in conjunction with the length gage markings O, provide for the ready regulation of the lengths severed from the wire and for the accurate bending of the same, to form staples of different lengths.

In this manner staples may be cut and formed at a rapid rate, the wire being fed in through the opening D' with one hand and the handle lever operated by the other hand. This handle lever will necessarily be made of sufficient length to obtain the requisite cutting and bending power.

I claim—

1. A machine for use in making wire staples, formed by a flat table having a flange extending upward on one edge, the inner face of which extends at right angles to the table surface, an aperture made in such flange and extending at an acute angle to the line of its surface in from one end of the flange and out through the inner face thereof in a line with the table's surface, a slot formed across the table top beyond the exit of the said aperture, a disk plate mounted against the inner face of the flange to turn on a central axial pin and provided with a radially disposed knife blade that passes across the aperture exit of the flange when the disk is turned, a handle lever attached to such disk and a forked claw pivoted upon such handle lever and passing downward through the slot in the table top, substantially as specified.

2. In the machine for making wire staples described in claim 1, forming the vertical flange with an extension at one end beyond the corresponding end of the table, such extension having a knife blade inner top edge, and providing the said lever handle with a knife blade secured along its edge, that when the handle is turned back, will shear across

the knife blade edge of the said extension, substantially as and for the purposes specified.

3. In the machine for making wire staples described in claim 1, an adjustable gage plate fastened to the table top beyond the slot therein and adapted to be engaged by the end of a wire caused to project through the aperture in the table flange, substantially 10 as specified.

4. A machine for making wire staples characterized by being formed with a table, a vertical extension at one edge of such table having an aperture extending through it 15 and emerging at an acute angle on to the surface of the table, a cutter mounted on

such extension and adapted to sever with an angle cut, a wire end projected through the aperture, a slot in the table top across which such projecting wire end passes, and 20 a device adapted to pass down through the said slot and to engage and double up the said severed wire end, substantially as specified.

In testimony whereof I have signed this 25 specification in the presence of two subscribing witnesses.

FREDERICK WILLIAM RASMUSSEN.
